UNITED STATES PATENT OFFICE.

STEPHEN THRWEAT BUTLER, OF SOCORRO, TERRITORY OF NEW MEXICO.

STIRRUP.

SPECIFICATION forming part of Letters Patent No. 380,276, dated March 27, 1888.

Application filed August 10, 1887. Serial No. 246,600. (No model.)

To all whom it may concern:

Be it known that I, STEPHEN THRWEAT BUTLER, a citizen of the United States, and a resident of Socorro, in the county of Socorro and 5 Territory of New Mexico, have invented certain new and useful Improvements in Stirrups; and I do hereby declare that the following is a full, clear, and exact description of the invention, which will enable others skilled in the 10 art to which it appertains to make and use the same, reference being had to the accompanying drawings, which form a part of this specification, and in which—

Figure 1 is a rear view of my new and improved stirrup. Fig. 2 is a detail view of the hinged spring-actuated gate of the same and of the bar on which the gate is hinged. Fig. 3 is a longitudinal vertical central sectional view of my improved stirrup, showing the foot 20 of the rider in position in the same; and Fig. 4 is a detail view of a modification of my invention.

The same letters of reference indicate corresponding parts in all the figures.

25 My invention relates to stirrups; and it consists in a new and improved hinged spring-actuated attachment or gate which is adapted to be secured in operative position to any stirrup, which prevents the toe from being pushed 30 too far through the stirrup, the lower end of the said gate being provided with a leather flap or cushion which prevents the upper part of the foot from being hurt by the metal of the gate, and which, in case of the rider being 35 thrown, will be swung back or raised by the toe, so as to free the feet from the stirrups, and thus prevent the rider from being dragged by the feet after being thrown from the saddle, as has heretofore occurred in many cases.

40 My invention will be hereinafter fully described and claimed.

Referring to the several parts by letter, A A indicate a stirrup of ordinary construction, having at its upper end the transverse bar B, 45 around which the stirrup-leather works. Just below this top bar, B, of the stirrup is secured a second transverse bar, C, on which the spring-actuated gate is hinged and works, the reduced ends of this lower bar, C, fitting in suitable 50 apertures in the sides of the stirrup at those points, and the bar C being adapted to be fit- ted to any stirrup by merely forming the apertures D D in the sides of the stirrup and fitting the reduced ends of the bar in the same. The enlarged middle portion of the bar C is 55 round in cross section and is formed on its rear longitudinal side with the central straight or flat portion or space, C', for the purpose hereinafter specified.

E indicates the hinged or swinging gate, 6c which may be formed of a single piece of metal, being struck out of the same and shaped by a suitable die, the upper end of this gate being formed with the rearwardly turned hooks F F, which fit over and around the 65 rounded portion of the bar C, while the lower side ends, G G, of the gate are extended out and curved at their free ends to form the hooks H H, which bear against or fit over the rear edges of the lower sides of the stirrup, as 70 shown. A flat spring, I, is secured at its lower end in the central portion of the gate, and its upper free end extends up and bears against the rear flat side, C', of the bar C. The lower or bottom edge of the gate E is curved 75 or rounded up to conform to the curvature of the top of the foot, and a flap, J, of leather or other suitable yielding material, is riveted to the lower edge or portion of the gate in the position shown and serves, when the foot of 80 the rider is thrust into the stirrup, to prevent it from being bruised or hurt by the lower edge of the metal gate, as will be readily seen.

The pressure of the spring I, secured at its lower end in the gate and bearing with its upper free end against the flat rear side of the bar C, on which the gate is hung, tends to keep the gate normally pressed forward, so that it normally stands in a nearly-vertical position, while the hooks H H at the lower ends 90 of the gate, bearing against the rear edges of the sides of the stirrup, prevent the lower end of the gate from being pushed through the stirrup forward by the pressure of the spring I, and also by the forward pressure of the 95 toe of the rider. It will thus be seen that when the rider places his feet in the stirrups the gate will prevent him from slipping his feet too far through the stirrup, as frequently happens, the upper part of the foot bearing 100 against the lower curved edge of the gate, while the leather flap or cushion J prevents

the metal of the gate from hurting or rubbing his feet. Now, in case of the rider being thrown from his horse, the backward pull of his toe will instantly raise (swing up) the gate 5 of each stirrup, thus freeing his feet instantly from the stirrups and preventing his being dragged to death, which often occurs, owing to the rider's feet being thrust too far through the stirrups, and thus preventing him from 10 freeing them when thrown from the saddle.

If preferred, I may employ the form of spring shown in Fig. 4 of the drawings without departing in the least from the spirit of my invention. In this form the spring is formed of 15 wire and coiled in opposite directions from the center, as shown, the central coiled portion of the spring being mounted upon (encircling) the bar C, while a pin or hook is inserted in the middle of the bar C, and the middle loop, L, of the 20 coiled spring is hooked over it to prevent this portion of the spring from moving on the bar, and the free straight ends M M of the spring then pass down and through apertures N N, which are formed in the gate near its side 25 edges, as shown. With the exception of these side apertures, the gate is formed as before described, the only differences in construction in the whole being the different form of spring, the pin or hook K, and the small side apertures, N N. I prefer, however, to use the 30 construction before described, and shown in Figs. 1, 2, and 3 of the drawings.

From the foregoing description, taken in connection with the accompanying drawings, the 35 construction, operation, and decided advantages of my invention will be readily understood.

It will be seen that my invention is simple and strong in construction and can be manufactured at a small cost, and that it is exceedingly efficient and satisfactory in its operation. 40 It forms a perfect safety attachment to any

stirrup, adds to the convenience of the stirrup while riding, and will prevent many serious accidents.

Having thus described my invention, what I claim, and desire to secure by Letters Patent of the United States, is—

1. The combination, with a stirrup, of a transverse bar arranged in the upper end of 50 the same, a gate hinged at its upper end on the said bar and formed with the side hooks or projections at its lower end, the leather flap or cushion secured to the lower edge of the said gate, and a spring normally pressing the lower 55 end of the gate forward.

2. The combination, with the bar adapted to be secured in the upper part of a stirrup, having the reduced ends, the rounded middle portion, and the flat rear side, of the gate 60 formed with the hooks at its upper end and the side hooks or projections at its lower end, and the spring secured at its lower end in the said gate and bearing with its upper free end against the flat rear side of the said bar, substantially as set forth.

3. The combination, with the bar adapted to be secured in the upper part of a stirrup, having the reduced ends, the rounded middle portion, and the flat rear side, of the gate 70 formed with the hooks at its upper end and the side hooks or projections at its lower end, the leather flap riveted to the lower edge of the said gate, and the spring secured at its lower end in the said gate and bearing with its 75 free upper end against the flat rear side of the said bar, substantially as set forth.

In testimony that I claim the foregoing as my own I have hereunto affixed my signature in presence of two witnesses.

STEPHEN THRWEAT BUTLER.
